UNITED STATES PATENT OFFICE

1,993,098

DEGREASING AGENT

Paul Hodges, Tuscaloosa, Ala., assignor to Gulf States Paper Corporation, a corporation of Delaware

No Drawing. Application April 20, 1933,
Serial No. 667,046

5 Claims. (Cl. 87—5)

My invention relates to degreasing agents, such as are employed for removing grease, oils, and oily or greasy substances, from metals, hides, concrete, board flooring or similar uses, and has 5 for an object the provision of such agents which shall contain as a principal ingredient thereof what is known in the paper industry as "floating soap."

"Floating soap" is that saponaceous product 10 which is formed in the black liquor produced in the digestion process in the production of paper or other cellulosic products by the sulphate or soda process, and which in part separates and floats to the top of the liquor drained from the 15 pulp after digestion, and which also is in part in solution in the liquor and may be separated out by centrifugal separation or other methods.

"Floating soap," so called, contains the alkali 20 salts of a complexity of fatty and resinous acids, higher alcohols, and a number of other compounds, many of which have not as yet been identified. While no dependable analysis of 25 "floating soap" is available, it is known to treat the product, for example, as set forth in the U. S. 25 patent to Michelson No. 1,823,752, in such a manner as to free the acid constituents and alcohols from the "floating soap" and obtain a complex mixture of such constituents which is known in the trade as "Tallol".

30 Among the compounds which have been identified in "floating soap" are the sodium salts of oleic acid, palmitic acid, linolenic acid, capric acid, and linoleic acid, and unidentified unsaponifiable compounds. (Hasselstrom Paper Trade 35 Journal, July 8, 1926, page 60; Chem. Abs. 20: 3566). Also in Sandquist, Berichte 64 B, pages 2172-4, (Chem. Abs. 26: 472) there are identified a salt of lignoceric acid, lignoceryl alcohol and phytosterol. Aschan in Finska Kem. Medd. 1918, 40 page 8, (Chem. Abs. 13: 2868), describes salts of pinabietic acid. Dittmer in Z. Angew Chem., vol. 39, page 262 (1926) (Chem. Abs. 20: 2072) describes abietic acid as well as confirming the work 45 of other investigators, and mentions other unidentified hydrocarbons.

E. Phyala in Svensk. Pappers Tid. vol. 29, 601-4, 627-9 (1926): (Chem. Abs. vol. 21, page 2072) separates the so-called "floating soap" according 50 to viscosity into twelve classifications ranging from easily mobile fatty oil to a black asphalt like resin. Among compounds not mentioned by other investigators and identified by this author are ricinoleic acid, erucic acid, erythrose and man- 55 nose.

Besides the above mentioned compounds, the so-called "soap" contains free sodium hydroxide, free sodium sulphide, free sodium carbonate, free sodium acetate, and other unidentified materials. The physical and chemical properties of different samples vary to a certain extent depending upon the conditions of manufacture and the woody material from which it is obtained.

My invention has for a further object the provision of a degreasing agent which shall contain as a principal ingredient "floating soap".

A still further object of my invention is the provision of a degreasing agent which shall contain any one or more of a number of known compounds having grease solvent properties, together 15 with "floating soap" and, in the case of emulsions, a stabilizing agent which may comprise any fatty acid, such as rosin or "tallol," or any mineral acid which will form a fatty acid with the "floating soap."

I have discovered that "floating soap" alone has remarkable penetrating properties, as well as excellent grease removing properties, and is also an effective agent for the removal of rust and paint from metal or wood surfaces. It may be 20 used alone or in a water solution with good results in many instances. When combined with other substances, such as hereinafter mentioned, having the property of dissolving grease, I have found that, due among other things to its penetrating qualities, it greatly enhances those properties and renders such solvents far more efficient.

Among the solvents which I have found to be especially useful might be mentioned trichlor- 35 ethylene, amylene dichlorides, ethylene dichloride, diacetone, isopropyl ether, carbon tetrachloride, mono methyl ethylene glycol ether, dioxan, acetone, ethyl lactate, mono ethyl ethylene glycol ether, dichlormethane, ethyl acetate, turpentine, kerosene, and gasoline. Other equivalent solvents will suggest themselves to those skilled in the art.

The amylene dichlorides mentioned above are sold on the open market and comprise a mixture of amylene dichlorides in which the chlorine 45 atoms are attached to adjacent carbon atoms.

One example of my invention, in the form of an emulsion, may comprise the following:

	Example 1	Parts
Trichlorethylene	60	
Oleic acid	3	
"Floating soap"	20	
Water	100	55

In making the above emulsion, the "soap," oleic acid and trichlorethylene are preferably mixed and stirred until a good solution is obtained. Water is then added with violent agitation until a smooth creamy emulsion is produced. The emulsion thus produced, I have found to be very stable, and I think permanent, sample batches made up in the manner described having stood for more than a month without separating out. The emulsion may be further diluted with water before use.

If desired, a finely divided abrasive, such as powdered flint, stack ash, silicon carbide or aluminum oxide, may be added to the emulsion when making it. The abrasive will be found to accelerate the removal of the grease from metal, wood, concrete, stone or other solid surfaces. Any desired amount may be added, though 5% will ordinarily be found to be sufficient.

The oleic acid mentioned in Example 1 acts as a stabilizer for the emulsion. In place of the oleic acid, I may use any fatty acid or mixture of fatty acids, such as rosin or "tallol," or any mineral acid which will form a fatty acid with the "floating soap." For example, the emulsion may be made up with trichlorethylene, slightly more "floating soap" than is set forth in Example 1, and sufficient phosphoric acid to react with the excess of "floating soap" to form the necessary stabilizer, "tallol". Where rosin is substituted for the oleic acid, a higher temperature is required in forming the emulsion, for obvious reasons.

Where "tallol" is substituted for the oleic acid, it produces equally good results, so far as the removal of grease is concerned, but the resulting emulsion is not quite so smooth as that produced with the oleic acid.

The composition described in Example 1, or an equivalent composition including equivalents of the solvents and stabilizers given, is effective for the removal of practically all greases. A somewhat more penetrating and faster working agent may be made, however, from a combination of solvents with the "floating soap." One example of such a solution made in accordance with my invention is as follows:

Example 2

	Percent
Trichlorethylene	37.5
Alcohol	37.5
"Floating soap"	25.0

The constituents are mixed and stirred cold until a good solution is obtained.

In the product given in Example 2, I have found that the solvent properties of trichlorethylene and alcohol are greatly enhanced by the "floating soap", due, in my opinion, to the remarkable penetrating properties which I have found that the "soap" possesses. With either the solution or the emulsion types, they may be employed in the manner common to degreasing agents. Metal articles and hides in tanneries may be degreased by simply dipping them into the composition. Floors may be scrubbed with the compositions greatly diluted, or the composition may be sprayed on to the surfaces to be degreased. Where large surfaces are to be cleaned, a power driven brush greatly facilitates the speed with which grease may be removed. The rate of removal may also be greatly accelerated by the addition of up to 5% of an abrasive to the emulsion, as heretofore described, and when so added to the emulsion, the abrasive will remain in suspension and will not settle out of the emulsion.

In removing grease from metal articles moving in a production line, it is often desirable to spray the metal with or immerse it in the removing compound. It is then sometimes desirable to have a composition that will more aggressively attack the grease coating. For this purpose I have found it desirable to form a solution comprising a solvent or combination of solvents, "floating soap" and a mineral acid. The most desirable mineral acid has been found to be phosphoric. One example of such a solution made in accordance with my invention is as follows:

Example 3

	Percent
Mono butyl ethylene glycol ether	30
Phosphoric acid-85% H ₃ PO ₄	50
"Floating soap"	20

The constituents are mixed and stirred until a good solution is obtained. It will be understood, of course, that the phosphoric acid entering into the solution combines in part with the "floating soap" to form "tallol." The remainder remains as free acid.

In the product given in Example 3, I have found that the solvent properties of mono butyl ethylene glycol ether are greatly enhanced by the "floating soap", and that the phosphoric acid aids in completely cleaning the surfaces. The solution given in Example 3 may be employed by dipping or spraying, followed by washing off with water.

In Example 3 "tallol" derived from "floating soap" may be substituted for the "floating soap." Other solvents such as mono butyl diethylene glycol ether, mono ethyl diethylene glycol ether, mono methyl ethylene glycol ether, butyl lactate, butyl alcohol, diacetone, dioxan, ethyl lactate, acetone, ethyl alcohol, methyl alcohol, isopropyl alcohol and similar solvents may be used.

Among the advantages and novel properties of "floating soap" as constituents of the emulsion or solvent type of degreasing agents are:

- (1) It presents a cheap emulsifying agent for the usual degreasing solvents.
- (2) It will emulsify practically any oil, grease or wax.
- (3) Any dirt, rust or scale particles are carried into suspension.
- (4) The penetrating properties of the "soap" allow it to penetrate beneath the particles of grease and oil and thus aid removal.
- (5) It is an excellent inhibitor for further rusting even when highly diluted with water.
- (6) It will remove tar, rust or paint present.
- (7) The wax content aids in staying on work.
- (8) The high water content of the emulsion tends to eliminate fire and fume hazard and greatly decreases loss of solvent during use and storage.
- (9) Any emulsion remaining on work may be washed off with water. No salts detrimental to electro-plating are present in any appreciable amounts.

(10) The film if left on work will not be detrimental to a new paint film.

(11) The emulsions are very stable to electrolytes and hydrolysis of the solvents appears to have little effect on their stability.

It will be obvious from the foregoing that I have devised an improved degreasing agent having incorporated as a principal ingredient therein "floating soap", which is extremely economical of manufacture, being made principally from a waste product of the paper industry, and which

is remarkably effective for the purposes described.

It will also be apparent that the proportions given in the examples recited herein are to be taken as illustrative only, and that they may be varied from widely, without departing from the spirit of my invention; and while I have described my invention in several forms, it will be obvious to those skilled in the art that it is not so limited, but is susceptible of various other changes and modifications, without departing from the spirit thereof. I desire, therefore, that only such limitations shall be placed thereupon as are imposed by the prior art or as are specifically set forth in the appended claims.

What I claim is:

1. A degreasing agent comprising an excess of 50% of two organic grease solvents, one a chlorinated hydrocarbon and the other alcohol, and the remainder "floating soap" obtained from the black liquors in the manufacture of soda or sulphate cellulosic material.

2. A degreasing agent comprising an organic grease solvent and "floating soap" obtained from

the black liquors in the manufacture of soda or sulphate cellulosic materials, the proportions of "soap" to the organic solvent being at least one to four.

3. A degreasing agent comprising trichlor- 5 ethylene, alcohol and "floating soap" obtained from the black liquors in the manufacture of soda or sulphate cellulosic material, the "floating soap" comprising substantially one-fourth of the active ingredients.

4. A degreasing agent comprising a chlorinated hydrocarbon grease solvent, "floating soap" obtained from the black liquors in the manufacture of soda or sulphate cellulosic material, sufficient higher fatty acid to stabilize the emulsion, 15 and water, the "floating soap" comprising substantially one-third of the active ingredients.

5. A degreasing agent comprising "floating soap" obtained from the black liquors in the manufacture of soda or sulphate cellulosic ma- 20 terial, phosphoric acid, and an organic grease solvent, the "floating soap" comprising more than 15% of the composition.

PAUL HODGES.
